(57) **CLAIM**

I claim the ornamental design for a coaxial and DSL cable switch for controlling a computer connection to the internet, as shown and described.

DESCRIPTION

FIG. 1 is a perspective view of a coaxial and DSL cable switch for controlling a computer connection to the internet showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

1 Claim, 4 Drawing Sheets

FIG.1.

FIG. 2.

FIG. 4.

FIG.3.

FIG.5.

FIG. 6.

FIG. 7.
